SURFACE MOISTENER

Filed April 25, 1929

UNITED STATES PATENT OFFICE

EMIL HEINEKE, OF PHOENIX, ARIZONA

SURFACE MOISTENER

Application filed April 25, 1929. Serial No. 358,055.

The invention primarily has for its object to provide a novel, simple and economically constructed device capable of being employed to moisten postage stamps, envelopes or other gummed surfaces, which is neat and attractive in appearance and which may be carried about or used easily and without inconvenience or danger of messy leakage of the moistening liquid while being so carried or when in actual use.

In its more detailed nature the invention resides in the provision of a novel fountain pen-like structure comprising a two-part casing, a moistening applicator mounting body or stock, a refillable liquid sac, and a novel feeder block and moistener applicator assembly for feeding the moistening liquid from the sac to the applicator and from the applicator onto the gummed surface in a sanitary and efficient manner.

Other objects will in part be obvious and in part be pointed out hereinafter.

To the attainment of the aforesaid objects and ends the invention further resides in the novel details of construction, combination and arrangement of parts, all of which will be first fully described in the following detailed description, then be particularly pointed out in the appended claims, reference being had to the accompanying drawings in which:—

Figure 1 is a perspective view of the moistener in the inactive cover applied condition.

Figure 2 is a perspective view illustrating the invention in use.

Figure 3 is a view illustrating the parts of the moistener separated and arranged in axial alignment.

Figure 4 is a central longitudinal section.

Figures 5 and 6 are cross sections taken on the lines 5—5 and 6—6 respectively on Figure 4.

Figure 7 is a detail perspective view of the feeder block.

In the practical development of the invention I provide a hollow cylindrical main casing body 1 of hard rubber or other suitable material and which is open at one end and closed at its other end. The open end of the body 1 is externally threaded as at 2 to pro-

vide a mounting for the end cover or cap 3 which, like the body 1, is substantially cylindrical in form and open at one end and closed at the other end, the said open end being internally threaded at 4 to receive the threads 2 of the body 1 and provide for the securing of the cap 3 on the said body. The closed end of the cap may be convex as at 5 to provide a burnishing end to facilitate the sealing act by pressing the parts to be sealed 60 tightly together.

The body 1 is also provided with a sac squeezer mechanism 6 which may be of conventional form and need not be further described in detail.

A stock body 7 is also provided and includes a reduced shank 8 to frictionally fit the open end of the casing body 1, and a further reduced shank 9 to receive the rubber sac or liquid reservoir 10. The body 7 also has a feeder block and applicator assembly receiving and fluid delivery bore 11.

All of the parts described above will be recognized as more or less conventional fountain pen parts, and their construction and manner of operation will be well understood without further comment.

In order to adapt these parts to the peculiar uses to which the invention is adapted, I provide a cylindrical feeder block 12 constructed of hard rubber or other suitable material and having formed in its peripheral surface a plurality of longitudinal feeder grooves 13 which pass through the receiving or inner end of the block as at 14 but flare outwardly at the delivery or outer end of the block as at 15, merging with the said end at its periphery so that they terminate at, but do not extend through, the end but leave the said end unbroken.

The moistener applicator is in the nature of a thin cylindrical shell 16 open at one end and split at 17 to provide a spring gripping end and closed at its other end to provide a solid head portion 18 adapted to extend beyond the feeder block 12 which the said shell is adapted to grip with retaining friction when the applicator shell and the feeder block are inserted as a unit into the receiving bore 11 of the stock body 7.

The applicator shell head portion end is provided with a plurality of transverse slits 19 which intersect at the longitudinal axis of the applicator and extend beyond the head 5 18 where each terminates in an enlargement 20 adapted to receive moistening fluid from one of the feed block grooves 13. It will be observed that each applicator slit 19 registers with one of the feeder block grooves 13. 10 The applicator shell is constructed of gold, gold filled or other suitable spring metal and the head slits 19 are very narrow and serve as capillary grooves which hold the moistening fluid against inadvertent leakage but 15 which allow a suitably copious flow when the flat end of the applicator is brought into contact with and moved over a surface to be moistened.

By manipulation of the sac squeeze equipment 6 with the applicator head immersed in moistening fluid in the manner customary in the use of the fountain pens, the sac 10 may be suitably filled with moistening fluid and the device made ready for use. In this condition the cap 3 may be applied and the device carried about without fear of undesirable leakage of the fluid.

When it is desired to moisten a surface it is only necessary to remove the cap 3 and 30 apply the head end of the applicator to the surface to be moistened. By moving the head about the surface a thin film of fluid will be released from the device and applied to the said surface in an efficient and sanitary 35 manner.

In the foregoing description, I have disclosed a simple form of mechanical moistener which can be conveniently carried about without fear of messy leakage and which 40 will serve to avoid the necessity of employing the unsanitary and harmful "mouth" method of moistening and also the use of more or less impractical exposed mechanical moisteners of other types which are themselves unsanitary and seldom in condition for immediate use when desired.

From the foregoing description, taken in connection with the accompanying drawings, it is thought that the novel details of construction, the manner of use and the advantages of my invention will be readily apparent to those skilled in the art to which it relates.

What I claim is:

55 1. A device of the character described comprising a casing having a moistening fluid reservoir and a delivery bore at one end, an applicator comprising a shell-like body open at one end and adapted to fit the bore of the 60 casing and to be frictionally held therein and having a closed end projecting from the bore and provided with a plurality of transverse intersecting capillary slits, a feeder block fitting within the applicator and having longitudinal grooves therein to receive fluid from

the reservoir and deliver it to the applicator slits.

2. A device of the character described comprising a casing having a moistening fluid reservoir and a delivery bore at one end, an applicator comprising a shell-like body open at one end and adapted to fit the bore of the casing and to be frictionally held therein and having a closed end projecting from the bore and provided with a plurality of transverse intersecting capillary slits, a feeder block fitting within the applicator and having longitudinal grooves therein to receive fluid from the reservoir and deliver it to the applicator slits, said grooves extending through one end of the block and terminating adjacent the other end of the block in communication with the applicator slits. 70 75 80

3. A device of the character described comprising a casing having a moistening fluid reservoir and a delivery bore at one end, an applicator comprising a shell-like body open at one end and adapted to fit the bore of the casing and to be frictionally held therein and having a closed end projecting from the bore and provided with a plurality of transverse intersecting capillary slits, a feeder block fitting within the applicator and having longitudinal grooves therein to receive fluid from the reservoir and deliver it to the applicator slits, said grooves extending through one end of the block and terminating adjacent the other end of the block in communication with the applicator slits, said slits having enlargements for communicating with said block grooves. 85 90 95 100

4. A device of the character described comprising a casing having a moistening fluid reservoir and a delivery bore at one end, an applicator comprising a shell-like body open at one end and adapted to fit the bore of the casing and to be frictionally held therein and having a closed end projecting from the bore and provided with a plurality of transverse intersecting capillary slits, a feeder block fitting within the applicator and having longitudinal grooves therein to receive fluid from the reservoir and deliver it to the applicator slits, said grooves extending through one end of the block and terminating adjacent the other end of the block in communication with the applicator slits, said applicator being split at its end opposite the slit equipped end to provide gripping portions for the purpose described. 105 110 115

5. In a moistener, an applicator shell open at one end and closed at the other end, said closed end being provided with transverse slits which intersect at the axis of the shell, and a feeder block shaped to fit the applicator shell and having longitudinal grooves therein communicating with the shell slits for the purpose described. 120 125

6. In a moistener, an applicator shell open at one end and closed at the other end, said 130

closed end being provided with transverse slits which intersect at the axis of the shell, and a feeder block shaped to fit the applicator shell and having longitudinal grooves therein communicating with the shell slits, 5 said shell slits terminating in enlargements for communicating with said block grooves.

7. In a moistener, an applicator shell open at one end and closed at the other end, said closed end being provided with transverse slits which intersect at the axis of the shell, and a feeder block shaped to fit the applicator shell and having longitudinal grooves therein communicating with the shell slits, 10 said shell slits terminating in enlargements for communicating with said block grooves, 15 said applicator shell also having its end opposite the slotted end split to provide gripping portions for the purpose described.

8. In a moistener, an applicator shell open at one end and closed at the other end, said closed end being slotted, and a feeder block shaped to fit into the applicator shell and having longitudinal grooves therein communicating with the shell's slits, and means for 20 delivering fluid to the open end of the applicator shell.

9. A device of the character described comprising a casing having an open end, a moistening fluid reservoir located in said casing, a stock body held in the open end of said casing and having a delivery bore, said reservoir being mounted on said stock body, an applicator mounted in said bore and adapted to 30 receive fluid from the reservoir and apply it on a surface to be moistened, said applicator comprising a shell-like body open at one end and closed at the other end, said closed end having transverse slits communicating with the interior of the shell-like body for the 35 purposes described.

10. A device of the character described comprising a casing having an open end, a moistening fluid reservoir located in said casing, a stock body held in the open end of said casing and having a delivery bore, said reservoir being mounted on said stock body, an applicator mounted in said bore and adapted to receive fluid from the reservoir and apply it on a surface to be moistened, said applicator comprising a shell-like body open 40 at one end and closed at the other end, said closed end having a plurality of transverse capillary slits which intersect at the axis of the applicator and communicate with the interior of the shell-like body.

11. A device of the character described comprising a casing having an open end, a moistening fluid reservoir located in said casing, a stock body held in the open end of said casing and having a delivery bore, said reservoir being mounted on said stock body, an applicator mounted in said bore and adapted to receive fluid from the reservoir 55 and apply it on a surface to be moistened,

said applicator comprising a shell-like body open at one end and closed at the other end, said closed end having a plurality of transverse capillary slits which intersect at the axis of the applicator and communicate with the interior of the shell-like body, and a cap 70 for closing over the applicator and having a convex end for the purpose described.

12. A device of the character described comprising a casing having an open end, a moistening fluid reservoir located in said casing, a stock body held in the open end of said casing and having a delivery bore, said reservoir being mounted on said stock body, an applicator comprising a shell-like body open 75 at one end and adapted to fit said bore and being frictionally held therein and having a closed end projecting from the bore and provided with a plurality of transverse intersecting capillary slits communicating with the interior of the shell-like body.
